UNITED STATES PATENT OFFICE.

FREDERICK P. POOLE, OF LA GRANGE, ILLINOIS, ASSIGNOR TO WESTERN ELECTRIC COMPANY, INCORPORATED, OF NEW YORK, N. Y., A CORPORATION OF NEW YORK.

ELECTROMAGNETIC APPARATUS.

1,262,838.

Specification of Letters Patent. Patented Apr. 16, 1918.

Application filed April 11, 1917. Serial No. 161,188.

To all whom it may concern:

Be it known that I, FREDERICK P. POOLE, a citizen of the United States, residing at La Grange, in the county of Cook and State 5 of Illinois, have invented certain new and useful Improvements in Electromagnetic Apparatus, of which the following is a full, clear, concise, and exact description.

This invention relates to electromagnetic 10 apparatus and has for its object the production of an electromagnetic structure in which the energizing winding may be accurately located and positively secured in definite relation to the end of its core.

Generally stated the invention relates to 15 an electromagnetic structure in which the energizing coil is wound as a solenoid on a hollow spool, which spool is adapted to be slipped over a core; the core is provided 20 with a seating portion adapted to serve as an abutment for an adjustable spacer interposed between one end of the spool and the said seat.

The invention resides more particularly 25 in providing in an electromagnetic structure, means whereby the energizing winding may be accurately located and definitely secured on a core and in a predetermined relation to the end thereof, wherein variations 30 in the dimensions of the individual parts of the structure may be compensated for at the time the said parts are assembled as a finished product, and whereby continuous production of finished structures 35 having uniform characteristics and of uniform efficiency is assured.

The invention is of particular importance 40 in its relation to telephone receivers where it has been found as the result of an extended investigation including a series of tests that the transmission efficiency is governed to a considerable extent by the relation between the energizing winding and the end of the core, and that variations in 45 the length of the portion of the core extending beyond the winding will cause variations in the transmission efficiency.

It has also been found upon investigation 50 that transmission efficiency increases as the length of the core extension beyond the winding is reduced, and that the best results are obtained by locating the winding as near as possible to the end of the core.

A better understanding of the invention may be obtained by referring to the drawing forming a part of this application, which shows the invention as employed in the construction of a telephone receiver and in which:

Figure 1 is a side view, in section, of the magnetic structure of a telephone receiver;

Fig. 2 is a side view of an electromagnet of the receiver shown in Fig. 1;

Fig. 3 is an end view of the electromagnet shown in Fig. 2 and illustrates the method 65 used in retaining the winding spool on the core; and

Fig. 4 is a detailed and side view of a portion of the rear end of the electromagnet of Fig. 2, showing the adjustable spacer introduced between the end of the spool and the seat or abutment on the pole piece or core.

The receiver illustrated in Fig. 1 comprises among other things a horseshoe permanent magnet 1, provided with extended 75 pole pieces 2 of reduced cross section, a pair of magnetizing coils 3, an inclosing cup 4 for the pole piece extensions 2 and the coils 3, and a diaphragm 5. The rim of cup 4 is adapted to serve as a seat for the periphery 80 of the said diaphragm 5.

The coils 3 are wound on bobbins consisting of two flanges 6 and 7, mounted on a tube 8, all composed of suitable insulating material such as paper, rubber or fiber, and 85 in the preferred form of bobbin one end of the tube is extended a short distance beyond the flange 6. The internal dimensions of tubes 8 are such that the tubes will slide over the ends of the pole piece extensions 2 and make a snug fit. Metallic washers 10 are used for the purpose of retaining the coils on the pole extensions and the openings in the washers are of practically the same dimensions as the forward ends of the said 95 extensions.

Portions of each of the pole piece extensions are cut away, leaving the forward ends of such extensions narrower than the rear ends, and providing shoulders 9 adapted to 100 serve as abutments as shown in Fig. 4. The forward narrow portions are made slightly longer than the length of the tubes 8.

In the assembly of the coils in the magnetic structure, the bobbins are slipped over 105 the ends of the pole extensions and in such a

position that the ends of the tubes 8 projecting beyond the flanges 6 are brought into engagement with the abutments 9. The washers 10 are then also slipped over the forward ends of the pole piece extensions and pressed into engagement with the flanges 7 of the bobbins. Lugs 11, struck out of the body portions of the washers, project slightly into the opening through the central portions thereof. These lugs grip the sides of the pole extensions and hold the said washers in place, which washers, in turn, hold the coils 3 in place on the pole extensions.

15 The complete magnetic structure, except the diaphragm, is then inserted into a suitable machine and pressure is applied to the washers 10, and they are forced along the pole extensions until the ends of such extensions extend a predetermined distance beyond the said washers. The pressure applied to the washers 10, in addition to forcing the washers along the pole extensions, also forces the bobbins with their windings 20 as a whole along the said pole extensions, but inasmuch as the tubes of the said bobbin spool are of a suitable material such as paper, rubber or fiber, the portions of the said tubes 8 extending beyond the flanges 6 25 are compressed or crumpled, and as a result permit the coils to move along the pole extensions far enough to permit the coils to be located at the predetermined position, and at the same time serve the purpose of 30 an adjustable spacer between the flanges 6 of the bobbins 3, and the abutments 9. The extended portions of the tubes 8 in their engagement with abutments 9 also provide a

means for holding the bobbins in engagement with the washers 10.

As an alternative method of assembling the coils into the magnetic structure, and in accordance with this invention, the ends of the tubes 8 may be made flush with the flanges 6, and separate elements in the shape 45 of the tubes 8 and of any suitable material, may be slipped over the pole extensions prior to the placing of the bobbins thereon, and the said separate tube sections will 50 serve as adjustable spaces when the pressure is applied to the washers 10 for the purpose of seating the coils on the pole extensions in their predetermined positions.

What is claimed is:

1. In an electromagnet, the combination of 55 a core, an abutment on said core, a bobbin adapted to slip over said core, a retaining washer for said bobbin, and a yielding spacing element between said bobbin and said abutment, whereby said bobbin is held in a 60 position determined by said retaining washer.

2. In an electromagnet, the combination with a core, an abutment formed on said core, a bobbin adapted to slip over said core, 65 a retaining device for said bobbin adapted to fit over the said core and to engage therewith, and a compressible spacing element on said core between the abutment and one end of said bobbin adapted to permit the bobbin to assume, under pressure, a predetermined position, and to maintain the said bobbin in said predetermined position.

In witness whereof, I hereunto subscribe my name this 2nd day of April, A. D. 1917.

FREDERICK P. POOLE.
